UNITED STATES PATENT OFFICE

2,441,787

FIRING MECHANISM FOR GUNS

Ernest Zryd, Beloit, Ohio

Application October 11, 1946, Serial No. 702,639

2 Claims. (Cl. 42—69)

1

My invention relates to firing mechanism for guns.

An important object of my invention is to provide means for firing a gun when the butt of such gun is pushed against the shoulder of the user.

A further object of the invention is to provide a convenient and superior way to fire a gun, for snap shooting at moving game, and for trap and skeet shooting.

A further object is to provide means, alternate with the conventional trigger, for firing a gun, which means are particularly useful to persons who have lost fingers, or who are wearing heavy gloves, as when duck hunting in cold weather.

A still further object of the invention is to provide a novel firing mechanism for guns, which is simple, positive in action, and inexpensive to incorporate in the design of certain guns.

Other objects and advantages of the invention will be apparent during the course of the following description.

In the accompanying drawings, forming a part of this application, and in which like numerals are employed to designate like parts throughout the same,

Figure 1 is a central vertical longitudinal section through the stock of a gun, and illustrating the firing mechanism embodying my invention.

Figure 2 is an end elevation of the butt of the gun, and,

Figure 3 is a transverse section taken on line 3—3 of Figure 1.

In the drawings, wherein for the purpose of illustration is shown a preferred embodiment of my invention, the numeral 4 designates an automatic gun, such as is shown in Patent 1,347,756. This gun comprises a stock 5 including the usual small of the stock 6. The stock has a butt plate 7. Secured to the small of the stock 6, is a trigger guard 8, enclosing a trigger 9, pivoted at 9'. This trigger 9 corresponds to the trigger 63 in Patent 1,347,756. The trigger 9 extends above and below its pivot 9. When the upper end of the trigger is moved forwardly, the gun is fired.

The stock 5 is provided in its butt end with a recess 10, which also passes through the butt plate 7. This recess is rectangular. Mounted to reciprocate within the recess 10 is a shoulder plunger 12, which is also rectangular. This shoulder plunger is adapted to project rearwardly beyond the butt plate 6. The shoulder plunger 12 has spaced parallel rods 13 and 14 rigidly secured thereto. The rod 13 is slidably mounted in a guide sleeve 15, held stationary within an

2

opening 16 formed in the stock 5. The rod 13 has a stop 17 rigidly secured to its forward end, to engage the sleeve 15 and limit the rearward movement of the shoulder plunger 12. A compressible coil spring 18 is arranged in the forward end of the opening 16, to engage the stop element 17. The rod 14 is slidably mounted in a sleeve 19, held stationary in an opening 20 formed in the stock 5. The rod 14 has a stop element 21 rigidly secured thereto to engage with the sleeve 19 and limit the outward movement of the shoulder plunger 12. The opening 20 is continued in a reduced portion 22. A ring 23 slidably receives the rod 14 and engages a compressible coil spring 24, engaging the stop element 21. The opening 22 extends through the small of the stock 6 and receives in its forward end a guide sleeve 25, slidably receiving the rod 14. The forward end of this rod is arranged to contact with the trigger 9 above its pivot, to move the upper end of the trigger forwardly, to fire the gun, when the shoulder plunger 12 is moved forwardly. The upper end of the trigger 9 has been slightly modified for coaction with the rod 14, but the trigger 9 is substantially the trigger shown in Patent 1,347,756.

It is thus seen that when it is desired to fire the gun it is not necessary to pull the lower end of the trigger, but by shifting the stock 5 rearwardly with relation to the shoulder plunger 12 which is held against movement by engagement with the shoulder, a relative movement is effected between the rod 14 and the trigger 9, and the upper end of the trigger above the pivot 9' is moved forwardly and the gun fired.

The invention is not restricted for use in connection with the gun shown in Patent 1,347,756, but may be used in connection with other guns which are fired when the upper end of the trigger is moved forwardly, such as shown in Patents 1,025,132 and 1,073,588.

It is to be understood that the form of my invention herewith shown and described is to be taken as a preferred example of the same and that various changes in the shape, size, and arrangement of parts may be resorted to, without departing from the spirit of my invention or the scope of the subjoined claims.

Having thus described my invention, what I claim is:

1. A gun including a stock and a pivoted trigger extending above and below its pivot, said stock being provided at its butt end with a recess, a reciprocatory shoulder plunger mounted for movement within the recess, a rod connected with

the shoulder plunger and extending longitudinally of the stock and having its forward end arranged to move the upper end of the trigger above its pivot forwardly, and yielding means to oppose the movement of the shoulder plunger into the recess.

2. A gun including a stock and a pivoted trigger extending above and below its pivot, said stock having a recess at its butt end and longitudinally extending openings leading into the recess, substantially parallel rods mounted within the longitudinal openings to reciprocate therein, a reciprocating shoulder plunger mounted within the recess and secured to the rods, springs mounted within the openings and serving to 15 shift the rods toward the butt end of the stock, one rod having its forward end terminating ad-

jacent to the trigger at a point above the pivot of the trigger to exert a force upon the trigger to swing its upper end forwardly.
